B. SCHECHTER,
WINDOW FRAME,
APPLICATION FILED MAY 20, 1920.

Patented Nov. 23, 1920.

Benjamin Schechter Inventor
By his Attorney

UNITED STATES PATENT OFFICE.

BENJAMIN SCHECHTER, OF ST. LOUIS, MISSOURI.

WINDOW-FRAME.

1,359,624.

Specification of Letters Patent. Patented Nov. 23, 1920.

Application filed May 20, 1920. Serial No. 383,012.

To all whom it may concern:

Be it known that I, BENJAMIN SCHECHTER, a citizen of the United States, and a resident of the city of St. Louis and State of Missouri, have invented a certain new and useful Improvement in Window-Frames, of which the following is a specification.

The object of this invention is to construct a window frame in such a manner that the sash can be placed in position and removed very readily, and when placed in position will be held snugly in place, thus preventing it from rattling, likewise preventing the passage of air between the sash and frame when the sash is in closed position.

The invention is particularly adapted for railway passenger cars and more especially when the window frames and sashes are of wood, but it will be understood that they can be made of metal and can be used in any place where a snug-fitting sash is desired, particularly where the frame and sash are subject to vibration and rattling of the sash is likely to be caused thereby.

With these objects and other objects which may hereinafter appear in view, I have devised the particular arrangement of the parts hereinafter set forth and more particularly pointed out in the claims annexed hereto.

Reference is to be had to the accompanying drawing forming a part hereof, in which—

Figure 1 is a front elevation of a portion of a window frame provided with my improvement.

Fig. 2 is a transverse section of the same.

Fig. 3 is a side elevation of the same with parts broken away to more clearly disclose the construction.

Fig. 4 is a side elevation of one of the filler blocks and

Fig. 5 is a plan view of the same.

Throughout the various views of the drawing, similar reference characters designate similar parts.

In the preferred embodiment of my invention, as illustrated in the accompanying drawing, 1 indicates one of the vertical side posts or stanchions of a passenger car, separating one of the windows from another. These posts are T-shaped in cross section thus having laterally-extending side webs 2 and an outstanding web 3.

Secured to the outstanding web 3 of the

post are a plurality of spaced-apart filler blocks 4. One of these blocks is disclosed in Figs. 4 and 5, where it will be seen that the same is provided with a central, longitudinally extending, aperture 5 and flanges 6, 60 which are provided with perforations 7. Each filler block 4 is provided with a slot 8 between the flanges 6 and the outstanding web 3 of the post 1 fits into the slot 8 and is thus embraced by the flanges 6. Screws or 65 rivets 9 pass through the projections 7 in the flanges 6 and through the web 3 of the post to hold the blocks in position projecting from the outstanding web 3 of said post.

Each block is provided with a boss 10 into 70 which is adapted to be threaded a screw 11, as will be hereinafter explained.

The window frame is provided on each side of the post 1 with longitudinally extending side members 12 which extend the 75 entire length of the window frame and are co-extensive with the post. It will be noted that the side members 12 are provided with inclined or beveled edges 13 to bear against the beveled edges of the sashes and form 80 the angular grooves for the reception of these window sashes 14. By reason of a construction to be hereinafter described, the side members 12 have a tendency to spring apart and the beveled edges 13 are thus 85 caused to bear against the angular edges of the sashes causing the sashes to be likewise held against the inner faces of the webs 2 on the post.

The sashes are thus resiliently held in 90 their grooves or guide ways in such a manner as to obviate looseness and rattling at all times.

At 15 is shown a longitudinally extending narrow strip. Secured to the strip by 95 screws 16 is a plate 17, the side edges of which are hinged, as at 18, to plates 19 and are secured to the side members 12. The hinges are preferably placed intermediate 100 of the spacing blocks. Secured to the side members 12 by screws 20, are leaf springs 21 which project downwardly and bear against the sides of the inwardly extending web 3 on the post 1. These springs 21 cause the side members 12 to be normally sprung 105 outwardly and they thus cause the beveled edges 13 on the side members 12 to be held snugly against the beveled edges 14 of the sashes as heretofore explained. Secured over the strip 15 is a lining strip 22 which is 110 wider than the strip 15. By this construc-

tion, curtain grooves or guide ways 23 are formed and the openings to said guide ways are narrowed by reason of longitudinally extending plates 24 secured to the side members 12.

5 The sashes may be readily and expeditiously removed by the removal of the screws 11, which permits the entire frame unit consisting of the strips 15 and 22 and side members 12 to be removed.

10 I have shown the window frame having the post 1 provided with resiliently mounted side members 12 at both of its sides. At certain times, it will be understood that the 15 flexibly or resiliently mounted members 12 may be placed on only one side of the post. This occurs especially at the ends of the car where a post is not situated intermediate of two windows.

15 20 Having described my invention, it is obvious that the same is not to be restricted to the exact embodiment shown, but is broad enough to cover all structures coming within the scope of the annexed claims.

25 What I claim is:

1. In a structure of the class described, the combination of a post, projections extending from said post, a member secured to said post, side members hinged to said member and springs secured to said side members and bearing against the post.

30 2. In a structure of the class described, the combination of a post, a pair of side members pivoted adjacent said post and 35 movable toward the sides thereof and leaf

springs secured to the inner faces of said side members and bearing against the post.

3. In a structure of the class described the combination of a post having an inwardly extending web and a pair of laterally extending side webs, a plurality of blocks secured to the inwardly extending web, a longitudinal strip secured to said blocks, a pair of side members hinged to said strip and springs extending between the 45 sides of the post and the side members.

4. A structure of the class described comprising the combination of a post having a pair of laterally extending webs, a pair of side members pivotally secured adjacent the 50 sides of the post and pivotally movable toward the same and springs extending between said side members and the sides of the post and adapted to resiliently resist movement of the side members toward the 55 post, said side members having angular edges coöperating with the faces of the lateral webs to form sash-receiving guideways.

5. A structure of the class described comprising a post, a member secured adjacent the same, a plate secured to said member, side plates pivoted to said plate, side members attached to said plates and movable toward the sides of the post and springs secured to said plates and bearing against the 60 sides of the post.

Signed at the city of St. Louis, and State of Missouri, this 11th day of May, 1920.

BENJAMIN SCHECHTER,
